BELT BUCKLE OR SIMILAR ARTICLE

Harry Stelzer, New York, N. Y.

Application September 24, 1952, Serial No. 21,557

Term of patent 3½ years

(Cl. D17—1)

To all whom it may concern:

Be it known that I, Harry Stelzer, a citizen of the United States of America, residing in New York city, county of New York, and State of New York, have invented a new, original, and ornamental Design for a Belt Buckle or Similar Article, of which the following is a specification, reference being had to the accompanying drawing, forming part thereof,

Fig. 1 is a plan view of a belt buckle or similar article, showing my new design.

Fig. 2 is an edge view thereof.

Fig. 3 is a plan view of the belt buckle as shown in Fig. 1 in open position.

I claim:

The ornamental design for a belt buckle or similar article, substantially as shown.

HARRY STELZER.
